WYCOFF ROBBINS, OF HANCOCK COUNTY, ILLINOIS.

Letters Patent No. 91,771, dated June 22, 1869.

IMPROVED DITCHER

The Schedule referred to in these Letters Patent and making part of the same.

To all whom it may concern:

Be it known that I, WYCOFF ROBBINS, of Hancock county, in the State of Illinois, have invented certain new and useful Improvements in Ditchers or Scrapers; and I do hereby declare that the following is a full and exact description thereof, reference being had to the accompanying drawings, making part of this specification, in which—

Figure 1 is a top view of my improved ditcher.

Figure 2 is a rear view of same.

Figure 3 is a front view.

The nature of my invention consists in providing a rapid means of making roads, ditches, hedge-rows, and throwing dirt up to plank fences.

To enable others skilled in the art to make and use my invention, I will proceed to describe its construction and operation.

I construct a wooden frame, A A, shod with plate-steel on the bottom, to prevent wear, hinged at f f.

On one wing of the frame is attached a flange, C, of steel, and on the other wing is attached a steel flange, B.

The point of the ditcher is covered with plate-steel, running far enough back on the side of the hinge f f

to cover it and prevent the earth from entering the joint.

The centre and rear of the frame are provided with double bars D D, secured by screws at o o, and with slots e e and screws m m, to enable the frame to be widened or narrowed, to suit the gauge of the work to be performed.

The gear is attached to the forward part of the frame A A, by a chain or anything else suitable, passing through i, and fastening with a clevis and pin at l.

What I claim as my invention, and desire to secure by Letters Patent, is—

1. The frame A A, when constructed with flanges B and C, and secured by a hinge, f f, all operating substantially as and for the purpose set forth.

2. Also, the combination of the frame A A, flanges B C, connecting-bars D D, hinge f f, clevis-holes l l, hitching-holes i i, when the same are constructed and arranged substantially as and for the purpose described.

WYCOFF ROBBINS.
